UNITED STATES PATENT OFFICE

BENJAMIN F. HARTWELL, OF WINCHESTER, MASSACHUSETTS

MACHINE FOR MAKING LAMINATED COUNTER BLANKS AND OTHER ARTICLES

Application filed January 29, 1929. Serial No. 335,953.

The object of this invention is to provide a machine whereby an operator may quickly and conveniently assemble layers of sheet material, and cause cement applied to two or 5 more of said layers to adhesively unite the layers and thereby produce a laminated article which may be, for example, a blank adapted to be molded into heel counter form by a subsequent operation.

10 Of the accompanying drawings forming a part of this specification,—

Figure 1 is a perspective view of a machine embodying the invention.

Figure 2 shows in perspective a laminated 15 blank producible by the machine, the layers at one end of the blank being separated from each other.

Figure 3 is a much enlarged section on line 3—3 of Figure 2.

20 Figure 4 is a front elevation of the machine, parts shown by Figure 1 being omitted.

Figure 5 is a section on line 5—5 of Figure 4, showing parts omitted from Figure 4, the pressing beds hereinafter described 25 being in their receiving positions.

Figure 6 is a view similar to Figure 5, omitting the treadle, and showing the beds in their pressing positions.

Figure 7 is an enlargement of a portion of 30 Figure 6.

Figure 8 is a fragmentary perspective view, showing certain details.

The same reference characters indicate the same parts in all of the figures.

35 I will now describe the machine as organized to produce counter blanks. It will be obvious, however, that the machine may be organized to produce other laminated articles.

40 The machine comprises a pair of pressing beds 12, having perforations 13, and constituting members of suction boxes, the air spaces of which are designated by 14, the beds forming side walls of the box. Edge and end

45 walls of the boxes may be formed by marginal enlargements 15, formed on the beds, and the boxes may be completed by side walls 16 and packing gaskets 17, all as shown by Figure 7.

50 It is obvious that suction boxes communi-

cating with the perforations 13 of the beds may be otherwise provided. Said perforations permit the confinement of blank layers on the beds by atmospheric pressure, when air is exhausted from the boxes, as hereinafter 55 described.

Hinges are provided connecting the beds with fixed supporting means, such as frame members 18, fixed to a bench 19, suitably elevated above a floor. In this instance, the 60 hinges include hinge socket members 20, formed on adjacent edges of the beds, and a hinge pintle member 11, secured to the frame members 18, and extending through the socket members 20, the arrangement being 65 such that the hinges permit the beds to alternately occupy the receiving positions shown by Figures 1, 4 and 5, and the pressing positions shown by Figures 6 and 7.

Each bed is provided with registration 70 means for locating a blank layer 21 thereon, in position to register with another layer 21 on the other bed, when the beds are moved to their pressing positions. In this instance, I have embodied the registration means in 75 straight outwardly facing longitudinal shoulders 22, adjacent the inner edges of the beds, each shoulder being provided with a projection 23, formed to enter a notch 24 (Figure 2) in the straight edge of each of the blank 80 layers.

Air may be exhausted from the suction 85 boxes by any suitable means, to cause the adhesion to the perforated beds of blank layers 21 deposited thereon by an operator. In this instance, I have embodied said means in a vacuum pump 25, shown conventionally by Figure 1, and a conduit connecting the air intake of the pump with the suction boxes, said conduit including a rigid section 26, and 90 two flexible sections 27, connecting the section 26 with the boxes, the sections 27 being of sufficient length and flexibility to permit movement of the beds from each of the positions shown to the other.

The machine comprises operating mechanism whereby foot or other power may be exerted on the beds to move them from their receiving to their pressing positions. Said mechanism is preferably embodied in a lever 100

29, fulcrumed between its ends on a fixed support, such as a rod 30, fixed at its ends to the frame members 18, one of said ends being shown by Figure 8, the portion of said lever at opposite sides of the fulcrum constituting an inner and an outer arm, power-applying means, such as a treadle lever 31, pivoted to a fixed ear 31^a, below the bench 19, and connected by a rod 32 with the inner arm 10 of the lever 29, and a pair of connecting links 33, pivoted at 34 to the outer arm of the lever 29, and pivotally connected with the pressing beds, preferably by ears 35, formed on the suction box walls 16, and pivots 35^a connecting said ears with the links. 15

The outer arm of the lever 29 and the links 33 constitute a three-part toggle, adapted to be made active as shown by Figure 6, to force the beds to their pressing positions, and inactive, as shown by Figure 5, to permit the beds to assume their receiving positions. 20

When the toggle is inactive, it constitutes an element of means for supporting the beds normally in their receiving positions, another 25 element of said means being a pad 36, preferably of leather, fixed to the bench 19, and constituting a stop which limits the downward movement of the toggle and the beds. The machine may be operated by an operator 30 standing beside it, who deposits a layer 21 on each bed, the beds being in their receiving positions. The layers are immediately caused by atmospheric pressure to adhere to the beds, and are then coated on the upper sides with 35 cement. An intermediate layer 21^a is then placed on one of the secured layers and caused to adhere thereto by the cement coating. The beds are then moved to their pressing positions and press together the layers thereon, 40 so that they are united by the cement coating and constitute a laminated blank, which is removable when the treadle 31 is released and the beds are returned to their receiving positions by gravity or by a pulling-down spring 45 38, connected with the outer arm of the lever 29, and with a fixed holder 38^a (Figure 1), the spring being arranged to be tensioned by movement of the lever to the position shown by Figure 6.

50 The described machine is particularly adapted for use in making blanks from two facing layers 21 of thin leather, and a thicker and stiffer intermediate layer 21^a of leather-board, or other suitable material. The margin of the intermediate layer is skived to a thin edge, as is best indicated by the enlarged sectional view (Figure 3), the layers 21 being too thin to be skived.

60 The completed blank has a straight edge 40 (Figure 2), which is the edge of the counter flange, subsequently formed from the blank, and a curved edge 41, which is the upper edge of the formed counter body. It is desirable that the marginal portions of the layers 65 which collectively form the curved edge 41,

be pressed closely together, so that said edge will be compact and well defined, and will not be objectionably thick. I therefore attach to one of the beds 12 a plate 42, having an elongated curved beveled face 43, formed and arranged to press a portion of the margin of one of the layers 21 against a skived marginal portion of the intermediate layer 21^a, and thus provide said layer 21 with a beveled portion 21^b, extending to the curved edge 41, as shown by Figure 3. The straight edge 40 of a counter blank does not require similar treatment, and the layers composing said edge may well be left in the condition indicated by Figure 3. 70 75 80

The plate 42 may be detachably secured, as by screws, to the bed by which it is carried, so that it may be removed when its use is not required, or replaced by another plate differently formed. 85

I claim:

1. An assembling machine for making laminated articles, comprising a pair of perforated beds, each constituting a member of a suction box, means connecting said beds with fixed supporting means, and adapted to permit the beds to alternately occupy receiving and pressing positions, each bed having registration means for locating a layer thereon in position to register with a layer on the other bed, air-exhausting means communicating with the suction boxes to cause adhesion of the layers to the beds, and operating mechanism for swinging the beds from their receiving to their pressing positions, to press together cement coated layers carried by the beds, means being provided for supporting the beds normally in their receiving positions. 90 95 100 105

2. An assembling machine as specified by claim 1, the registration means of each bed being embodied in an outwardly facing longitudinal shoulder adjacent the inner edge of the bed, provided with a projection formed to enter a notch in the inner edge of a layer laid on the bed. 110

3. An assembling machine as specified by claim 1, one of said beds having a pressing face formed to transversely incline a longitudinal edge portion of a layer carried by said bed. 115

4. An assembling machine as specified by claim 1, the operating mechanism being embodied in a lever fulcrumed between its ends on a fixed support and having inner and outer arms, power-applying means connected with the inner arm, and a pair of connecting links pivoted to the outer arm of the lever and pivotally connected with the beds, the outer lever arm and the connecting links constituting a three-part toggle, adapted to be made active to force the beds to their pressing positions, and inactive to permit the beds to assume their receiving positions. 120 125 130

5. An assembling machine as specified by

claim 1, the said operating mechanism being embodied in a lever fulcrumed between its ends on a fixed support and having inner and outer arms, power-applying means connected with the inner arm, and a pair of connecting links pivoted to the outer arm of the lever and pivotally connected with the beds, the outer lever arm and the connecting links constituting a three-part toggle, 10 adapted to be made active to force the beds to their pressing positions, and inactive to permit the beds to assume their receiving positions, the machine comprising also a fixed stop adapted to cooperate with the said toggle in supporting the beds normally in their receiving positions.

In testimony whereof I have affixed my signature.

BENJAMIN F. HARTWELL.
